US00D624797S

(12) **United States Design Patent**
Kochi et al.

(10) **Patent No.:** US D624,797 S
(45) **Date of Patent:** ** Oct. 5, 2010

(54) **MANUAL CABLE CUTTER**

(75) Inventors: **Minoru Kochi**, Niigata-ken (JP);
Sadayoshi Kobayashi, Niigata-ken (JP)

(73) Assignee: **Toa Intersystem Inc.**, Niigata-Ken (JP)

(**) Term: **14 Years**

(21) Appl. No.: **29/311,996**

(22) Filed: **Aug. 20, 2009**

(30) **Foreign Application Priority Data**

Feb. 23, 2009 (JP) 2009-003640

(51) **LOC (9) Cl.** 08-05

(52) **U.S. Cl.** D8/52

(58) **Field of Classification Search** D8/4,
D8/5, 14, 22, 23, 51-56, 58-60, 105-107;
81/300, 302, 415-424, 424.5, 426, 426.5,
81/427, 427.5; 30/244-262

See application file for complete search history.
